Primary Examiner — Lauren R Calve*(74) Attorney, Agent, or Firm* — Cantor Colburn LLP**CLAIM**

The ornamental design for a confectionery packaging, as shown and described.

DESCRIPTION

FIG. 1 is a perspective view of a confectionery packaging, showing our new design;

FIG. 2 is a front view of FIG. 1;

FIG. 3 is a rear view of FIG. 1;

FIG. 4 is a side view of FIG. 1;

FIG. 5 is another side view of FIG. 1;

FIG. 6 is a top view of FIG. 1; and,

FIG. 7 is a bottom view of FIG. 1.
